PETER A. JORDAN, OF PHILADELPHIA, PENNSYLVANIA, ASSIGNOR
TO MACKELLAR, SMITHS, AND JORDAN, OF SAME PLACE.

Design No. 3,272, dated December 1, 1868.

DESIGN FOR PRINTERS' TYPE.

The Schedule referred to in these Letters Patent and making part of the same.

To all whom it may concern:

Be it known that I, PETER A. JORDAN, (assignor to MACKELLAR, SMITHS, and JORDAN,) of the city and county of Philadelphia, in the State of Pennsylvania, have originated and designed a new Design for a Printing-Type; and I do declare the following to be a full, clear, and correct description thereof, reference being had to the accompanying drawings, making a part of this specification, in which the capital and small letters of an entire alphabet are shown, made in accordance with my design, which design is preserved in the numerals and other signs or symbols made.

Having thus described my invention, What I claim as new, and desire to secure by Letters Patent, is—

The within-described design for a printing-type as herein shown.
